TOASTER

Dudley C. Pulliam, Chicago, Ill., assignor to Chicago Electric Manufacturing Company, Chicago, Ill., a corporation of Illinois

Application January 15, 1952, Serial No. 18,067

Term of patent 14 years

(Cl. D81—10)

To all whom it may concern:

Be it known that I, Dudley C. Pulliam, a citizen of the United States, residing in Chicago, Cook County, State of Illinois, have invented a new, original, and ornamental Design for a Toaster, of which the following is a specification, reference being had to the accompanying drawing, forming a part thereof.

Fig. 1 is a front perspective view of a toaster showing my design;

Fig. 2 is a front elevational view thereof; and
Fig. 3 is an end view thereof.

The end not shown is like the end shown and the back is substantially plain.

I claim:

The ornamental design for a toaster, as shown and described.

DUDLEY C. PULLIAM.
